UNITED STATES PATENT OFFICE.

FREMONT P. LIVINGSTON, OF WILKINSBURG, PENNSYLVANIA, ASSIGNOR TO THE WESTINGHOUSE AIR BRAKE COMPANY, OF PITTSBURG, PENNSYLVANIA, A CORPORATION OF PENNSYLVANIA.

BRAKE-RIGGING FOR SIX-WHEELED TRUCKS.

SPECIFICATION forming part of Letters Patent No. 781,797, dated June 23, 1903.

Application filed October 18, 1902. Serial No. 127,806. (No model.)

To all whom it may concern:

Be it known that I, FREMONT P. LIVINGSTON, a citizen of the United States, residing in Wilkinsburg, in the county of Allegheny and State of Pennsylvania, have invented a certain new and useful Improvement in Brake-Rigging for Six-Wheeled Trucks, of which improvement the following is a specification.

10 My invention relates to brake-rigging for railway-cars, and has for its object to provide an improved form of brake-rigging particularly adapted to be used on six-wheeled trucks.

15 With this object in view my invention comprises a new and improved brake-rigging having brake-shoes applied to both sides of each pair of wheels.

It also consists in an equalized system of 20 brake-rigging having brake-shoes applied to both sides of each pair of wheels and which, together with the brake-cylinder, may be mounted on the truck and adapted to equalize all braking strains throughout the system 25 without straining any of the members of the truck-frame; and it further consists in certain novel combinations and improved features of construction, all as hereinafter more fully set forth.

30 In the accompanying drawings, Figure 1 shows a longitudinal section of a six-wheeled truck with my improved form of brake-rigging applied thereto. Fig. 2 is a plan view of the brake-rigging, a portion of the truck-frame and brake-beams being broken away; and Fig. 3 is a broken end view of the same.

According to the construction shown in the drawings, the brake-cylinder 1 is mounted upon the truck-frame, the piston-rod 2 being 40 pivotally connected to cylinder-lever 3, one end of which is connected to the equalizing brake-lever 5, while the other end is connected by means of pull-rod 4 with the corresponding lever 6, which is fulcrumed on a bracket or slack-adjuster 7, secured to a cross-beam at the opposite end of the truck. Brake-beams 8, 9, 10, 11, 12, and 13, provided with the usual hangers, are suspended from the truck-frame and arranged so as to bear on

both sides of each pair of wheels. On the 50 brake-beams are pivotally mounted the respective brake-beam levers 14, 15, 16, 17, 18, and 19, having the intermediate lower and upper rod connections 20, 21, 22, 23, and 24, respectively. The equalizing brake-lever 5 is connected at its lower end by a link 25 to the upper end of brake-beam lever 14, while at an intermediate point it is connected by means of a pull-rod 26 with corresponding equalizing-lever 27 at the opposite end of the 60 truck, this latter lever being connected at its upper end to lever 6 and at its lower end by link 28 to the upper end of brake-beam lever 19. The pull-rod 26 may be connected directly to the brake-beam lever 19 if desired. 65 The brake-cylinder is supported on brackets or bars secured to a cross-beam of the truck-frame, and in order to relieve said beam and also the corresponding beam carrying the slack-adjuster from any bending movement 70 due to braking stresses a compression-strut 29 is inserted between these points on the cross-beams. It will thus be seen that all strains due to braking will be equalized throughout this improved system of brake-rigging and 75 that all members of the truck-frame will be relieved from any such strains. The piston-rod or push-bar may be provided with a link or hook 30 for attachment to a hand-operated brake device, if desired.

When the brakes are applied, the power will be transmitted by means of the equalizing-lever 5 and rod 26 to brake-beam levers 14 and 19 at opposite ends of the truck and will then equalize through the system of 85 brake-beam levers and their upper and lower rod connections, thus applying all of the brake-beams to the wheels with equal pressure and equalizing all the strains throughout the system.

In many of the six-wheeled truck-brake designs heretofore used the brake-beams are applied to the outer side only of the outer pairs of wheels and to but one side of the center pairs of wheels, and it has been found 95 with this construction that the lateral pressure upon the journal-bearings, due to the pressure of the brake-shoes, has caused these

bearings to wear unevenly. Another objection to this old form of brake-rigging is that it produces a tilting of the truck-frame, due to the dragging movement of the outside 5 brake-beams, which tends to pull down one end of the truck-frame and to push up the other end. With my improved design of 10 brake-gear having brake-beams applied to both sides of each pair of wheels these objections are avoided, since the tilting tendency produced by the brake-beams on one side of the wheels is counteracted by that of the 15 brake-beams on the other side, and the brake-shoes being clasped to both sides of the wheels with equal pressure the journal-bearings are relieved of any lateral pressure due to braking strains.

Having now described my invention, what I claim as new, and desire to secure by Letters 20 Patent, is—

1. A brake-rigging for six-wheeled trucks, comprising brake-beams applied to both sides of each pair of wheels, brake-beam levers pivoted on the respective brake-beams, connections between said brake-beam levers, an 25 equalizing-lever pivotally connected to one of said brake-beam levers, and means connecting said equalizing-lever to another of said brake-beam levers.
2. In a brake-rigging for six-wheeled trucks, the combination with brake-beams applied to both sides of each pair of wheels, levers pivoted on said brake-beams, and connections between said levers, of an equalizing- 35 lever pivotally connected to one of the end brake-beam levers, and means connecting said equalizing-lever to the brake-beam lever at the other end of the truck.
3. In a brake-rigging for six-wheeled 40 trucks, the combination with brake-beams applied to both sides of each pair of wheels and a lever pivoted on each of said brake-beams, of rods connecting the levers of each pair of brake-beams, other rods connecting the levers of adjacent brake-beams of different 45 pairs, an equalizing-lever pivotally connected

to one of the end brake-beam levers, and means connecting said equalizing-lever with the other end brake-beam lever.

4. In a brake-rigging for six-wheeled 50 trucks, the combination with brake-beams applied to both sides of each pair of wheels, levers pivoted on the said brake-beams, and alternate lower and upper rod connections between said brake-beam levers, of an equalizing-lever pivotally connected to each of the 55 end brake-beam levers, a rod connection between said equalizing-levers and means for applying power to said equalizing-levers.

5. In a brake-rigging for six-wheeled 60 trucks, the combination with brake-beams applied to both sides of each pair of wheels, levers pivoted on said brake-beams, and connections between said levers, of a brake-cylinder mounted on the truck, a cylinder-lever, 65 and an equalizing-lever with connections for operating said brake-beam levers.

6. In a brake-rigging for six-wheeled trucks, the combination with brake-beams applied to both sides of each pair of wheels, 70 levers pivoted on said brake-beams and connections between said levers, of a brake-cylinder mounted on the truck, a cylinder-lever and separate connections from the cylinder-lever to the two outer brake-beam levers. 75

7. In a brake-rigging for six-wheeled trucks, the combination with brake-beams applied to both sides of each pair of wheels, levers pivoted on said brake-beams, and intermediate rod connections for said levers, of a 80 brake-cylinder mounted on the truck, a cylinder-lever, a corresponding lever fulcrumed on the truck, a rod connecting these levers, and equalizing-levers connected to said cylinder-lever and corresponding lever 85 for operating the brake-beam levers.

In testimony whereof I have hereunto set my hand.

FREMONT P. LIVINGSTON.
